UNITED STATES PATENT OFFICE.

SHERMAN A. HATHORNE, OF WAUKEGAN, ILLINOIS, ASSIGNOR TO CHICAGO HARDWARE FOUNDRY COMPANY, OF NORTH CHICAGO, ILLINOIS, A CORPORATION OF ILLINOIS.

LUNCH-ROOM TABLE.

1,357,050.

Specification of Letters Patent. Patented Oct. 26, 1920.

Application filed February 16, 1920. Serial No. 359,135.

To all whom it may concern:

Be it known that I, SHERMAN A. HATHORNE, a citizen of the United States of America, and a resident of Waukegan, in 5 the county of Lake, State of Illinois, have invented certain new and useful Improvements in Lunch-Room Tables, of which the following is a specification.

This invention relates to that class of 10 tables used in lunch rooms and like places, and has for its object:

To provide a simple and efficient structural formation and association of table parts whereby lightness and strength are 15 provided with ample knee room, and which is adapted to effectively receive the usual coating of vitreous enamel now used on the various lunch room fixtures for sanitary reasons, all as will hereinafter more fully 20 appear.

In the accompanying drawings:

Figure 1, is a perspective view, with parts removed, of a lunch table of an extended form and embodying the preferred construction of the present invention.

Fig. 2, is a detail longitudinal section.

Fig. 3, is a detail transverse section on line 3—3 Fig. 2.

Fig. 4, is a detail horizontal section on 30 line 4—4 Fig. 2.

Fig. 5, is a perspective view illustrating a modified form of the invention as applied to any ordinary length of lunch room tables, the table top being removed to disclose the 35 detail construction of parts.

Fig. 6, is a longitudinal section of the modified structure.

Fig. 7, is a detached perspective view of adjoining portions of a supporting leg, and 40 a longitudinal connecting rail of the modified structure.

Like reference numerals indicate like parts in the several views.

Referring to Figs. 1 to 4 inclusive, of the 45 drawings, 1 designates a supporting leg of the present structure of a rectangular hollow form in cross-section throughout, and comprising in detail a central vertical member 2; a horizontal transverse lower member 3 and downturned members or feet 3' at the 50 respective ends of the lower member 3 aforesaid.

4 designates a connecting girder or rail which in the preferred form of the present

invention is of an open or latticed type, of 55 cast metal and having longitudinal upper members 5 of a T shape in cross-section and intermediate and end vertical members 6 of a rectangular form in cross-section, as shown.

7 designate a pair of attaching bolts arranged in vertically separated relation and passing through the end members 6 of the girder 4, and through the upper part of a vertical member 2, of a supporting leg 1, to 60 attain a substantial fastening of the parts together.

8 designates a marginal rectangular frame of an angle plate form in cross-section, fixedly attached to the upper ends of the central vertical members 2 of the supporting leg 1, to provide a support for the usual flat top 9 of the table, and which is usually formed of a slab of white vitreous material with a view to superior sanitary conditions. When a table of an extended length is required one or more intermediate supporting legs 1, will be employed, and the marginal supporting frame as well as the table top 9 will be made in sections, to 70 meet the requirements as to table length.

Referring to Figs. 5 to 7 inclusive of the drawings, a single unit table is shown, comprising a pair of end supporting legs 1 of a similar construction to the legs heretofore 85 described, and a single piece of marginal supporting frame 8 attached to laterally extending flanges 10 integrally formed on the upper parts of the central vertical members 2 of the supporting legs 1.

The modification shown in Figs. 5 to 7 inclusive, differs from the rail or girder shown in Figs. 1 to 4 inclusive, in the employment of a rail or girder 11 of structural angle metal, which is bolted or otherwise 90 secured to central vertical ribs or flanges 12 on the upper ends of the central vertical members 2 of the supporting feet 1, as shown more particularly in Figs. 6 and 7.

Having thus fully described my said invention what I claim as new and desire to secure by Letters Patent, is:

1. In a table, the combination of a plurality of legs, each formed with a hollow rectangular central vertical member and a 105 hollow rectangular lower horizontal member having downturned ends of a like hollow rectangular form, the parts being integrally

- formed as a single piece casting, a central connecting girder fixedly attached to the upper ends of the aforesaid central vertical members, a marginal frame of an angle 5 form in cross-section secured to the upper ends of said central vertical members, and a table top resting on said marginal frame and girder.
2. In a table, the combination of a plurality of legs, each formed with a hollow rectangular central vertical member and a hollow rectangular lower horizontal member having downturned ends of a like hollow rectangular form, the parts being integrally 10 formed as a single piece casting, a central connecting girder fixedly attached to the upper ends of the aforesaid central vertical members, a marginal frame of an angle 15 form in cross-section secured to the upper ends of the said central vertical members by lateral flanges on said members, and a table top resting on said marginal frame and girder.
3. In a table, the combination of a plurality of legs, each formed with a hollow rectangular central vertical member and a hollow rectangular lower horizontal member having downturned ends of a like hollow rectangular form, the parts being integrally 20 formed as a single piece casting, a central connecting girder fixedly attached to the upper ends of the aforesaid central vertical members, a marginal frame of an angle 25 form in cross-section secured to the upper ends of the said central vertical members by lateral flanges on said members, and a table top resting on said marginal frame and girder.

casting, a central connecting girder fixedly attached to the upper ends of the aforesaid central vertical members, and comprising upper and lower members of a T form in cross-section, a marginal 35 frame of an angle form in cross-section secured to the upper ends of said central vertical members, and a table top resting on said marginal frame and girder.

4. In a table, the combination, of a plurality of legs, each formed with a hollow rectangular central vertical member and a hollow rectangular lower horizontal member having downturned ends of a like hollow rectangular form, the parts being integrally 40 formed as a single piece casting, a central connecting girder fixedly attached to the upper ends of the aforesaid central vertical members and comprising upper and lower members of a T form in cross-section and a 45 series of vertical members rectangular in cross-section, a marginal frame of an angle form in cross section, secured to the upper ends of said central vertical members by lateral flanges on said members, and a table 50 top resting on said marginal frame and girder.

Signed at North Chicago, Ill., this 11th day of February, 1920.

SHERMAN A. HATHORNE.
